CLAIM

The ornamental design for a hang up cup, as shown and described.

DESCRIPTION

FIG. 1 is a top, left, front, perspective view of a hang up cup;
FIG. 2 is a rear elevation view thereof;
FIG. 3 is a right elevation view thereof;
FIG. 4 is a bottom plan view thereof; and,
FIG. 5 is a top plan view thereof.

The broken line showing of FIG. 1 and FIG. 5 are for illustrative purposes only and form no part of the claimed design.
